HOUSE MODEL

Frank Bolhuis, Holland, Mich.

Application February 14, 1938, Serial No. 190,385

4 Claims. (Cl. 35—16)

The present invention relates to house models, and more particularly to structures adapted for use by architects, contractors, or lumber companies for demonstration and selling purposes.

5 The subject matter herein shown and described is of the general character shown and described in my co-pending application, Serial No. 130,437, filed March 12, 1937 and subsequently issued into Patent No. 2,118,338, dated May 24, 1938.

10 The primary objects of the instant invention are to provide such a model having an improved frame for the reception and retention of interchangeable wall panels, said frame being adjustable both as to length and as to width; to provide improved means for securing together in vertical series a plurality of one story frame sections with their respective panel receiving slots in vertical alignment; and, to provide in such a frame, corner members and panel receiving corner bars of simple and economical construction and of especial adaptability for their intended use.

15 An illustrative embodiment of the invention is shown in the accompanying drawing, wherein:

Figure 1 is a perspective view of the house model, certain wall panels being omitted and certain other wall panels being shown fragmentarily and in raised positions;

20 Figure 2 is an enlarged perspective view of an upper corner of a first story frame section and an adjacent lower corner of a second story frame section;

25 Figure 3 is an enlarged sectional view on line 3—3 of Figure 2;

30 Figure 4 is a sectional view similar to Figure 3 showing a modified form of construction; and

35 Figure 5 is a reduced elevational view of the parts shown in Figure 4.

Referring then to the drawing in which like numerals refer to like parts in the several views, 40 the house model shown in Figure 1 comprises a first story frame section designated generally 10, a second story frame section secured to the first story section and designated generally 11, a gable roof 12 resting on top of the second story section 11, and suitable wall and floor panels hereinafter described in detail.

45 The frame sections 10 and 11 are identical in construction for economy of manufacture and of course more sections may be added in vertical series if desired to produce a model having a greater number of stories.

50 The several upper and lower corner members 13 are also identical in construction, each of said corner members 13 being made from a single blank of metal and comprising a middle right tri-

angular horizontally disposed web 14 having screw receiving apertures therethrough, and right triangular sides 15 integral with the web 14 and extending vertically from the adjacent right angularly intersecting edges of the web 14, these sides 15 forming right angles with the web 14 and also forming a right angle between themselves. The farthest ends or points 16 of sides 15 are flanged inwardly one upon the other and spot welded at 17, thus making a rigid unit of each 10 corner member 13.

Vertically disposed corner rails 18 of identical construction are each formed of a single metal strip bent longitudinally to form parallel side flanges 19 and 20 providing therebetween a panel 25 receiving slot 21 and which corner rails are connected together along their middle portions 22 as by spot welding.

The wider side flange 20 of each of these corner rails 18 is secured at its opposite ends to vertically aligned sides 15 of a vertically spaced oppositely disposed pair of corner members 13, as by spot welding 37. The connecting middle portion 22 of each corner rail 18 forms an angle of substantially 45 degrees with the sides 15 of the corner 25 members 13 so that a pair of such corner rails may be secured to the exterior corners of the corner members with their connecting middle portions 22 in flush contact.

Horizontally disposed side rails 23 of angle iron 30 construction are spot welded at 24 to the inner vertical and horizontal surfaces of each corner member 13 and each side rail 23 extends horizontally from its corner member 13 to telescopically slidably engage a side rail of the opposite corner member 13. One of these mutually engaging side rails 23 may be somewhat larger than the other, having its marginal edges 25 flanged over to embrace the marginal edges of the smaller rail, as best seen in Figure 3. 40

Each horizontal and vertical flange of these side rails 23 is provided with a series of apertures 26 and fastening means such as bolts 27 and nuts 28 may be secured in registering apertures 26 of the mutually engaging side rails 23 to rigidly connect the rails in longitudinally adjusted relation. In this manner the frame sections are adjusted both as to width and as to length to accommodate wall panels 29 of desired widths, the marginal edges of which wall panels are received and retained in slots 21 of corner rails 18 and which wall panels bear representations of the walls of a house. 50

The modified rail fastening means shown in Figures 4 and 5 comprises a cross sectionally right 55

triangular wedge member 38 having screws 39 threaded therein. This wedge member 38 may be slidably inserted between the smaller side rail 23 and the flanged edges 25 of the larger side rail, the screws 39 then being tightened to engage in the angle of the smaller rail, the acute angular corners of the wedge 38 abutting the flanged edges 25 of the larger rail. In this modification, the side rails 23 need not be provided with apertures 26.

In the simulation of a two story structure, the second story frame section 11 is secured on top of the first story frame section 10 by means of bolts 30 passing through aligned apertures in the adjacent upper corner members 14 of the lower section 10 and lower corner members 14 of the upper section 11. Thus the corner rails of the two sections are aligned and wall panels of suitable height bearing representations of a two story structure may be inserted in the aligned panel receiving slots 21.

The flanged-over points or ends 16 of sides 15 of the corner members 13 form supporting ledges 31 which are utilized in the first story of the model to support a floor panel 32, the upper surface of which bears any selected floor plan 33 of a house. Using the selected floor plan as a guide, suitable partitioning 34 may be installed within the structure and the floor panel 32 being spaced from the bottom of the frame, representation of the foundation of the house may be made upon the outer wall panels 29.

In the upper story of the model, the floor panel 35 may be disposed upon the horizontal flanges of side rails 23 and may also bear a floor plan upon its upper surface to serve as a guide in the installation of partitions 36.

It will thus be seen that the frame structure herein shown and described may be adjustably assembled and utilized for the demonstration of many examples of house construction, that the parts of the model are all rugged and sturdy yet simple in construction and that the several parts may all be rigidly secured together.

While but several specific embodiments of the invention have been herein shown and described, it will be understood that certain details of the constructions shown may be altered or omitted without departing from the spirit of this invention as the same is defined by the following claims.

I claim:

1. In a structure of the class described, a corner rail adapted to be secured to and form

a part of a skeleton frame, said rail having longitudinal parallel side flanges forming therebetween a panel receiving slot, one of said side flanges being adapted to be secured to a vertical surface of the frame, and a connecting middle portion forming with said vertical surface an angle of substantially forty five degrees whereby a pair of said corner rails may be secured to substantially right angularly intersecting vertical surfaces respectively with the said connecting middle portions of said pair of corner rails in flush contact.

2. In a structure of the class described, a frame comprising vertically disposed corner rails having longitudinal panel receiving slots, panels bearing representations of the walls of a house and having their opposite ends detachably inserted and retained within the oppositely disposed slots of adjacent corner rails, and side rails connected to said corner rails and extending laterally to longitudinally slidably engage side rails of the adjacent corner rails thus rendering selectively variable the distance between adjacent corner rails so that the latter may accommodate panels of different widths.

3. In a structure of the class described, a frame comprising vertically disposed corner rails having longitudinal panel receiving slots, panels bearing representations of the walls of a house and having their opposite ends detachably inserted and retained within the oppositely disposed slots of adjacent corner rails, side rails connected to said corner rails and extending laterally to longitudinally slidably engage side rails of the adjacent corner rails thus rendering selectively variable the distance between adjacent corner rails so that the latter may accommodate panels of different widths, and means for connecting mutually engaging side rails in adjustably slid positions.

4. In a structure of the class described, a frame provided with vertically disposed corner rails having longitudinal panel receiving slots, securing means for securing one such frame on top of another such frame with their respective corner rails in alignment, and panels bearing representations of the walls of a two-story house and having their opposite ends detachably inserted and retained within the upper and lower aligned slots of upper and lower corner rails at adjacent corners of the structure, said panels being substantially the height of the combined upper and lower frames.

FRANK BOLHUIS.
